CLAIM

The ornamental design for a dispenser, as shown and described.

DESCRIPTION

FIG. 1 is a perspective view of a dispenser embodying our new design;

FIG. 2 is a front view of the dispenser shown in FIG. 1;
FIG. 3 is a right-side view of the dispenser shown in FIG. 1;
FIG. 4 is a rear view of the dispenser shown in FIG. 1;
FIG. 5 is a left-side view of the dispenser shown in FIG. 1;
FIG. 6 is a top view of the dispenser shown in FIG. 1; and,
FIG. 7 is a bottom view of the dispenser shown in FIG. 1. The broken lines in the drawings show unclaimed subject matter only and form no part of the claimed design. The dashed dot lines in FIG. 4 immediately adjacent to the shaded areas in the figures represent the boundaries of the claimed design. None of the broken lines form any part of the claimed design.

1 Claim, 7 Drawing Sheets
